UNITED STATES PATENT OFFICE

MARTIN J. TROY, OF ATLANTIC HIGHLANDS, NEW JERSEY, AND FRED LIBBY
OF PAWLING, NEW YORK

PRINTING-INK ROLLER

Application filed July 7, 1928. Serial No. 291,007.

This invention relates to ink distributing rollers and in particular to a type through the medium of which a number of different colors of ink can be accommodated simultaneously.

In the printing art, it has been the custom heretofore, when straight run work of various colors was to be accomplished in a press simultaneously, to cut down the 10 position rolls which are arranged for revolving and reciprocating movement in order to spread ink upon the print or plate engaging transfer roller with the result that printing cost was greatly increased due to 15 the fact that in a great many instances, special rollers had to be cut.

It is an object of our invention, therefore, to provide a roller construction, the sections of which may be made any length, can 20 be separated any distance apart and any number of different sections may be mounted upon a single shaft to provide for multi-color work in a single press.

A further object of our invention is to 25 provide in combination with roller pieces or rollers, a plurality of extension pieces which are relatively adjustable and through the medium of which the length of the rollers may be varied.

30 A still further object of our invention is to provide adjustable members for spacing the rollers the proper distance apart and also to provide a metallic ink transfer roller which will not be subject to wear or corrosion as is the case where composition rollers are employed.

To enable others skilled in the art to fully comprehend the underlying features of our 35 invention that they may embody the same in the various modifications in structure and relation contemplated, a drawing depicting a preferred form has been annexed as a part of this disclosure and in such drawing, similar reference characters denote corresponding 40 parts throughout all the views, of which,

Figure 1 is a view in elevation of an ink transfer roller constructed in accordance with our invention.

Figure 2 is an enlarged sectional view in 45 elevation of one end of the rollers, showing

how the same is locked in position on the shafts.

Figure 3 is an enlarged section taken on the line 3-3 of Figure 1 and illustrates the method of locking together the extension 55 pieces, the adjusters being also illustrated.

Figure 4 is an enlarged fragmentary view showing the connections between two sections of the roller, illustrating how the extension pieces may be manipulated through 60 the medium of the adjusters, and

Figure 5 is a view in perspective of one half of one of the extension pieces illustrating therein the undercut slot which is arranged to receive a tongue of the mating 65 piece whereby the extension pieces are locked together in sliding relation.

Figure 6 is a view on a smaller scale similar to Figure 4 showing the use of a modified form of spacer, and

Figure 7 is an end view of the spacer.

Referring to the drawings in detail, 5 indicates the usual operating shaft which is provided with the usual key-way 6 for accommodating the key 7, whereby the rollers 8 and the extension pieces 9 may be properly keyed to the shaft 5. The rollers 8 may be of any desired length and will probably be, in practice, of a standard 75 length, adjustment of the length thereof being provided for by the extension pieces. The rollers 8 and extension pieces may be made of metal in different forms, that is, a single alloy may be used for the entire 80 roller or the core of the roller may be made from one metal and covered with a different 85 wear-resisting metal so that the roller will be light and resist corrosion and can be manufactured cheaply.

In order to lock the rollers 8 and the extension pieces on the shaft 5, we have provided at one end of the shaft 5 a nut 10 which functions as a locking nut and which is arranged to abut against a locking ring 11 which is provided in its periphery with the 90 opening 12 so that it can be engaged by a spanner wrench. This locking ring as well as the nut 10 has threaded engagement with the shaft 5. The opposite end of the shaft 95 is also threaded as at 13 to receive a simi- 100

lar locking nut 14 and locking ring 15, the latter of which is provided with the spanner wrench openings 16 whereby it may be threaded into place against the adjacent extension pieces 9 and 17, these extension pieces constituting fillers and being identified as in the instance of extension piece 9 with a tongue 18 which is arranged to have sliding fit within the groove 19 formed in the extension piece 17. All of the extension pieces are constructed identically and any number of them can be placed adjacent the end of a roller 8 to increase the length thereof.

15 These extension pieces may also be made of any width desired and it is not necessary that the rolls be removed from the shaft in order that these extension pieces can be placed therebetween. It is simply necessary to revolve the adjusters 20 to bring the connected pieces 9 out of engagement with pieces 17 after which the pieces 17 will be free from the shaft. It will be particularly noted that the extension piece 9 is provided 25 with the key-way 21 so that it fits over the key 7 that extends substantially the length of the shaft 5.

In order that the proper spacing may be obtained between the divisions of rollers and 30 between the extension pieces, we have made use of adjusters 20 which are of solid or tubular construction and are threaded at their ends 21 and cooperate with threaded openings in the extensions 9 and 17 so that 35 by placing a suitable pin in the openings 22 thereof and revolving the same, the distance apart of the extension pieces can be adjusted.

It will be noted that the locking ring is 40 hollowed out as at 23 so that it is light and so that room is provided for the end of the key 7 which extends within said locking ring. The locking ring is of the same diameter as the extension pieces which are of a 45 diameter to coincide exactly with the diameter of the rollers and it is quite evident that any number of the rollers 8 may be used upon the shaft 5 and they may all be of a different length, depending upon the width 50 of the printing matter to be inked.

It is also evident that through the use of our improved rollers, a different number of inks may be used of various colors to provide one run through the press straight 55 printing of different colors.

The entire shaft 5 is reciprocated through the medium of the usual mechanism, not illustrated, but which is well known in the 60 art. The driving gear 24 is illustrated as being keyed as at 25 to the outer end of the shaft 5. It is of course understood that through the proper mechanism, the shaft 5 is rotated and reciprocated simultaneously 65 to spread the ink evenly upon an interme-

diate composition roll which distributes the ink to the type face.

In the modifications shown in Figures 6 and 7, use may be made of a semi-circular spacer 26 the ends of which may be positioned in slots 27 provided for that purpose in the extension pieces 9. These spacers may be of fixed lengths so that no measuring of the space between roller assembly need be made.

70 It is quite evident, therefore, that we have provided a new and improved ink roller which will accommodate a number of different colored inks which can be assembled so that the individual rollers are of different lengths and which will eliminate the necessity of cutting down composition rollers and the waste attendant thereto.

75 It will also be noted that means are provided for properly spacing the rollers apart after sufficient extension pieces have been employed to obtain the proper length of the sections of the rollers.

80 While we have illustrated and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the 85 appended claims.

90 Having thus described our invention what we claim as new and desire to secure by United States Letters Patent is:—

100 1. An ink roller for printing presses for distributing a plurality of different colored inks comprising a shaft, a plurality of rollers slidable therealong, extension pieces for abutment against the ends of the rollers for increasing their length and adjusting members connecting said extension pieces.

105 2. A printing press ink roller for distributing a plurality of different colored inks comprising a shaft, a plurality of rollers keyed thereto and slidable therealong extension pieces for abutment against the end of the rollers for increasing their length, adjusting members connecting said extension pieces and locking members at the ends of said shaft.

110 3. A printing press ink roller for distributing a plurality of different colored inks comprising a shaft, a plurality of rollers keyed thereto and slidable therealong, diametrically slit extension pieces for abutment against the ends of the rollers for increasing their length, a tongue and groove joining connection between the parts of said extension pieces and adjusting members cooperating with the said extension pieces for adjusting the space between them and the rollers.

115 4. A printing press ink roller for distributing a plurality of different colored inks comprising a shaft, a plurality of rollers keyed

thereto and slidably therealong, diametrically slit extension pieces for abutment against the end of the rollers for increasing their length, tongue and groove joining connections between the parts of said extension pieces, adjusting members having threaded connection with said extension pieces for adjusting the space between said rollers and extension pieces, and locking members at the ends of said shaft.

10 5. An ink roller for printing presses for distributing a plurality of different colored inks comprising a shaft, a plurality of rollers on the shaft, extension pieces for abutment against the ends of the rollers for increasing their length, and an adjusting member connecting some of said extension pieces.

15 6. An ink roller for printing presses for distributing a plurality of different colored inks comprising a shaft, a plurality of rollers on said shaft, extension pieces for abutment against the ends of the rollers for increasing their length and an adjusting member connecting some of said extension pieces.

20 25 In testimony whereof we affix our signatures.
